4 Claims. (Cl. 139—303)

The present invention relates to a shuttleless loom in which the filling threads are inserted from a stationary supply means of a reciprocating needle which moves transversely to the beater frame.

In this kind of looms it is necessary to cut the filling thread at the beginning of each filling stroke. On the other hand, in order to prevent the formation of a more or less irregular edge at the outlet side, it is also preferred to cut the ends which protrude from the edge of the fabric.

The invention has as principal object to provide a cutting mechanism for filler threads which operates with great accuracy.

The device according to the invention comprises a first blade which, in the rear position of the beater frame, is located immediately adjacent one end of the reed and parallel thereto, and a second blade which, in the same position, is directed towards the front of the loom, and disposed under the warp threads of the lower warp of a shed, both blades being carried by the beating frame and controlled by its movement to move towards each other after the insertion of the first filling thread.

It will be understood that with such arrangement the cutting of the filling thread is effected at a thoroughly accurate distance from the outermost warp threads or, in other words, from the edge of the fabric, as the transverse position of the warp threads is defined by the reed.

According to another feature of the invention, the blade which is arranged adjacent to the last reed tooth during the return motion of the beater frame, is stationary as regards the latter and does not turn while the second blade is turnable relative to the fixed blade about a transversal axis. Furthermore, the operating mechanism is regulated so that the blades close at the moment in which the beater frame comes forward. Owing to this arrangement, the movable blade is already raised when the point thereof comes to the withdrawing line, and when this point passes over the said line there is no risk of catching and cutting the auxiliary selvage thread between the blades, which thread is just tensioned in lateral direction and at the level of the said withdrawing line, as in the instant of the beating action the finger of the selvage device must be separated from the beater frame. At the same time, the closed blades, which are in vertical position at the side of the reed, cannot interfere with the adjacent fabric guiding device.

Where the loom is provided with a cutting device on either side of the beating frame, according to a further feature of the invention, the movable blade of each device is mounted on a shaft which is transversely mounted on the said beater frame and common to both devices, which, obviously, facilitates the construction as in this case it is only necessary to have a single operating mechanism in order to operate both devices. This mechanism may comprise a connecting rod articulated on the one hand to an arm mounted on the above transverse shaft and, on the other, to a fixed point.

In the case of a device intended for cutting the filling threads at the side of the loom which is opposite to the filling reserve, a suction nozzle is located on the beater frame so that the same sucks and holds in a tensioned condition the free end of the filler thread during the cut-

2

ting operation of the same. This nozzle is preferably mounted below the lower threads of the warp with the purpose of sucking downwardly the free end of the filler thread corresponding to the action of gravity for placing the free end against the second blade of the cutting device.

Other and further advantages and features of the invention will appear from the following detailed description of a preferred embodiment of the invention which is given only by way of one restrictive example.

FIG. 1 is a fragmentary schematic plan view of the left side of a shuttleless loom, showing only the essential members for understanding the present invention; FIG. 2 is a fragmentary plan view of the right side of the loom, and FIG. 3 is a diagrammatical side view on a larger scale, showing one of the cutting devices of the loom, respectively in the rear position of the beater frame (full lines) and in the forward position of the same (dotted lines).

In FIG. 1 and 2, the reference numeral 1 indicates the warp threads which go through the reed 2 carried by the beater frame 2a of the loom. The latter carries supply means for filling threads including four spools, not shown, from which four different filling threads 3a, 3b, 3c, 3d, issue, and thread guides 4a, 4b, 4c, 4d, arranged at the left side of the loom and holding the filling threads in a position to be picked up and drawn through the warp shed by means of a weft inserting needle 5, of reciprocating motion and operated from the right side of the loom (FIG. 2). The weft inlet side is located at the left of FIG. 1, while the outlet edge is located at the right side of FIG. 2. The guides 4a, 4b, 4c and 4d are located above the level of the needle 5 but are selectively lowered so that the said needle may catch one of the threads by means of a hook 6. The needle is provided with a conventional nip device in order to hold the thread picked as above and which opens when the said needle comes to the end of the stroke thereof, that is to say, in the position represented at the left hand side of FIG. 2. The free ends of the weft are held in tensioned condition at the left edge of the loom by suction means shown to be a sucking nozzle 7.

The finished fabric is held in tensioned condition in all the width thereof by means of two fabric guiding devices indicated at 8.

45 A selvage device is provided at each side of the loom and comprises a filler inserting finger 9, suitably articulated on a vertical shaft disposed over the corresponding fabric guiding device 8. For the sake of clarity, only the ends of the fingers 9 have been shown and it is assumed 50 that the operating mechanism with the vertical shaft and the arm connecting this shaft to the fingers have been withdrawn. Each finger is given a reciprocating motion with the purpose of inserting an auxiliary thread 11 through the warp at each time, this thread being held in 55 position when the finger 9 moves backwards and until the beating action, by means of a suitable needle, not shown, but the location of which is indicated at 12.

The beater frame 2a carries a cutting device according to the invention at each side of the reed 2. Each of the 60 said devices comprises a stationary blade 13 arranged at a short distance from the last tooth 14 of the reed (for example, about 1 mm.) and parallel thereto. The blade 13 is secured to the beater frame at the point 13a. A transverse shaft 15 crosses the blade and is arranged 65 under the lower threads of the warp 1. A corresponding movable blade 16 is mounted on shaft 15 so that in the rear position of the beating frame it is placed in a substantially horizontal position and directed towards the front end of the loom, that is to say, towards the right side of the FIG. 3 (the front end of the loom being, as usual, the end thereof where the fabric is coiled). On the other hand, the shaft 15 carries mounted thereon a

driving arm 17 to which a small connecting rod 19 is connected by a pivot joint 18, the said connecting rod being, in turn, articulated at the pivot pin 20 secured to a fixed support 20a on the stationary loom frame.

As it is shown in FIGS. 1 and 2, the shaft 15 extends through all of the width of the beating frame 2a, on which it is supported by means of two lateral supports 21. It carries the blade 16 of both cutting devices which, in this manner, are operated simultaneously by the small connecting rod 19.

Operation of the device is as follows:

When the beating frame is in its rear position indicated in full lines in FIG. 3, the cutting devices are in inoperative positions, the movable blades 16 of both cutting devices are under the path of the needle 5, and thereby, they do not interfere with the movement of the same. When the needle has moved backwards and inserted the filler thread through the warp, the beating frame 2a moves forward to a beating position shown in broken lines to beat the filler thread in the usual manner. In this movement the small connecting rod 19 forces the arm 17 to rock and the shaft 15 to revolve, moving each cutting device to a cutting position by applying the movable blade 16 of each cutting device against the corresponding fixed blade 13. It will be understood that with a suitable adjustment of the length of the small connecting rod 19 and of the position of its point of connection 20, it may be attained that the blade 16 takes the filler thread A and presses it against the fixed blade 13 during the forward motion of the beating frame to cut the thread. In such manner the filler is cut at an exact distance from the last warp threads 1 as the cutting means 13, 16 are secured to the reed 2 which guides these threads of the warp.

When the beater frame 2a arrives at its front position (indicated in dotted lines in FIG. 3), the blade 16 of each of the devices is raised towards the blade 13, so that there is no risk of an accidental cutting of the auxiliary filling thread 11; furthermore, the fabric guiding means 8 by no means interfere with the motion of the shears which, in turn, may be adjusted as desired.

FIG. 2 shows an additional aspiration nozzle 22, mounted on the beating frame 2a and constituting suction means arranged to suck and hold in tensioned condition the issuing end of the weft A just inserted by the needle, in order to facilitate the cutting of the said end and prevent the same from escaping from the shears. For the purpose of not disturbing the upper part of the right edge of the loom and to prevent any interference as regards the fabric guiding device and the corresponding selvage device, both located over the fabric, the said nozzle 22 is mounted so that its oval inlet opening 22a is located below the level of the lower threads of the warp 1 laterally of the same, with the axis of the inlet thereof directed at right angles to the plane of the fabric. This particular arrangement makes that the own weight of the thread acts in the same direction as the downward pull applied thereto by the sucking action of the nozzle, since gravity cooperates with the positive drawing thread by the nozzle. On the other hand the thus aspirated thread is held on the cutting edge of the movable blade and thereby is prevented from vibrating. It is also important to note that the nozzle being stationary as regards the beating frame, it follows the motion thereof and by no means can interfere therewith. The cutoff thread end is sucked into nozzle 22.

It is obvious, of course, that some modifications, regarding as size, shape and suitable materials, may be used in the present invention without departing from the scope thereof, the appended claims.

I claim:

1. In a loom in combination, a device for cutting the

ends of the fillings comprising a fixed support; a beating frame mounted on said support for a reciprocating movement between a rear position and a beating position, said beating frame having a reed means mounted thereon and adapted to extend across the warps with its ends located in the region of the outermost warps; a pair of first blades fixed on said beating frame and located directly adjacent the ends of said reed means, respectively; a shaft extending across the warps parallel to said reed means and being mounted on said beating frame for turning movement; a pair of second blades respectively mounted on the ends of said shaft and being turnable with the same between an inoperative position adapted to be located below the warps and a cutting position cooperating with said fixed first blades for cutting the fillings; and means secured to said support and operatively connected to said shaft for turning the same during movement of said beating frame so that said second blades are in said operative position when said beating frame is in said rear position, and so that said second blades are in said cutting position when said beating frame is in said beating position.

2. In a loom, in combination, a device for cutting the ends of the fillings comprising a fixed support; a beating frame mounted on said support for a reciprocating movement between a rear position and a beating position, said beating frame having a reed means mounted thereon and adapted to extend across the warps with its ends located in the region of the outermost warps; a pair of first blades fixed on said beating frame and located directly adjacent the ends of said reed means, respectively; a shaft extending across the warps parallel to said reed means and being mounted on said beating frame for turning movement; a pair of second blades respectively mounted on the ends of said shaft and being turnable with the same between an inoperative position adapted to be located below the warps and a cutting position cooperating with said fixed first blades for cutting the fillings; and means secured to said support and operatively connected to said shaft for turning the same during movement of said beating frame so that said second blades are in said rear position, and so that said second blades are in said cutting position when said beating frame is in said beating position.

3. In a shuttleless loom as set forth in claim 2, in combination, supply means for supplying fillings mounted on said support on one side of the warps; and suction means mounted on said support on the other side of the warps and adapted to suck in and hold the free ends of the fillings in tensioned condition.

4. A device as set forth in claim 3 wherein said suction means includes a nozzle located below the level of the lower warps of the warp sheds so that the ends of the fillings are downwardly deflected from the respective cutting means and so that cut-off ends of the fillings are removed.
